CLAIM

The ornamental design for an electropneumatic horn, as shown and described.

DESCRIPTION

FIG. 1 is a front perspective view of an electropneumatic horn showing our new design.

FIG. 2 is a front elevational view thereof.

FIG. 3 is a top plan view thereof.

FIG. 4 is a rear elevated view thereof.

FIG. 5 is a bottom plan view thereof.

FIG. 6 is a right side elevational view thereof; and,

FIG. 7 is left side elevational view thereof.

The broken lines depict unclaimed environmental subject matter.
